Filed Nov. 12, 1959, Ser. No. 58,309

Term of patent 14 years

(Cl. D61—1)

FIG. 1

FIG. 2

FIG. 3

Fig. 1 is a side perspective view of a slide projector showing our new design;

Fig. 2 is a side elevational view; and

Fig. 3 is a front perspective view thereof.

The opposite side, not shown, is conventional. The dominant features of our new design are shown in solid lines in the drawing. A portion of the drawing figures is stippled to indicate contrast in appearance. The broken line fragmentary showing of a slide tray in Fig. 3 is for illustrative purposes only.

We claim:

The ornamental design for a slide projector, substantially as shown and described.
